UNITED STATES PATENT OFFICE.

GEORGE P. WHITE, OF PARSONS, KANSAS, ASSIGNEE OF ONE-HALF TO S. P. ALQUIST,
OF DETROIT, MICHIGAN.

FURNACE.

1,252,210.

Specification of Letters Patent.

Patented Jan. 1, 1918.

Application filed July 13, 1914. Serial No. 850,711.

To all whom it may concern:

Be it known that I, GEORGE P. WHITE, a citizen of the United States, residing at Parsons, in the county of Labette and State 5 of Kansas, have invented certain new and useful Improvements in Furnaces, of which the following is a specification.

My invention relates to furnaces, and more particularly to a fluid fuel furnace 10 suitable for use as a blacksmith's forge or in other similar situations.

One of the principal objects of the invention is to provide, in a furnace of this type, certain new constructions and arrangements whereby the fuel is completely consumed and the heat developed is utilized to the full extent.

A further object is to provide a furnace in which the working or flames chamber in 20 which the metal or other articles are heated, is maintained at substantially a uniform temperature throughout.

The invention has in view particularly a stackless furnace involving the employment 25 of certain novel devices and constructions to be hereinafter more fully described for introducing the products of combustion into and forcing the same through the working chamber by means of air blasts, thereby saving the heat losses incident to a stack draft.

The invention consists furthermore in a construction of the working chamber and of means for introducing the flames into the same whereby the tendency of the flames to 35 issue from the working openings to the discomfort and inconvenience of the workman, is checked.

The invention consists further in the other novel and improved constructions, arrangements, devices and combinations relating to furnace construction which will be hereinafter described and claimed.

The invention is illustrated, in a preferred embodiment, in the accompanying 45 drawings in which—

Figure 1 is a side elevation of an oil burning furnace;

Fig. 2, a sectional plan taken on line 2—2 of Fig. 1;

Fig. 3, a longitudinal vertical section of the furnace on a larger scale;

Fig. 4, a cross sectional view on line 4—4 of Fig. 3;

Fig. 5, a fragmentary plan on line 5—5 of Fig. 4;

Fig. 6, an enlarged longitudinal sectional view of the burner, and

Fig. 7, a sectional perspective view of the furnace looking toward the bridge wall intended particularly to illustrate the movements of air through the air ducts and of the products of combustion through the combustion and working chambers.

Like characters of reference designate like parts in the several figures of the drawings.

The furnace structure consists of a metal shell 10 lined as usual with fire brick 11. 12 designates the working chamber and 13, a combustion chamber at one end thereof, 70 these two chambers being separated by a bridge wall 14. The working chamber is provided with any suitable number of working openings 15 through one side wall thereof, preferably near the floor 16. 75

If oil is to be burned as a fuel I preferably employ the burner best shown in Fig. 6. 17 designates an oil nozzle which is tapped into a fitting 18 with which the oil supply pipe 19 is connected. The oil nozzle 80 is surrounded by a compressed air nozzle 20 which is tapped into a fitting 21 to which extends a pipe 22 connected with a source of supply of compressed air (not shown). Surrounding the oil and compressed air 85 nozzles is an air blast pipe or nozzle 23 of considerably larger diameter than the other two, which has an opening 24 communicating with an air trunk 25 connected with a fan or blower (not shown). The upper ends 90 of the nozzles 17 and 20 are coned, as shown, with the result that the compressed air in the latter cuts off and atomizes the oil as it issues through the discharge orifice of the former. The end of the air blast pipe or 95 nozzle 23 is also flanged over as shown at 26 so as to direct the air blast against the flame. The structure 27 in which combustion chamber 13 is formed, is made with a loose brick 28 which can be removed for the 100 purpose of lighting the burner.

The burner above described is preferably arranged in vertical position with its upper end extending into the combustion chamber at the bottom, as shown. It produces a vertical flame upward through the combustion

chamber. My invention provides preferably a vertical or whirling air blast which is applied to the flames and gases of combustion from the burner at the back of the 5 combustion chamber and operates to carry said flames and gases of combustion over the bridge wall 14 and forward spirally through the working chamber as shown in Fig. 7. To accomplish this the end structure 27 of 10 the furnace is formed with two ducts 29, 30, which are directed one toward the other but at a slight angle, the duct 29 having a slight upward inclination and the duct 30 a slight downward inclination. These ducts are 15 connected to the main air trunk 25 by branch air pipes 31. The meeting of these two currents produces a vortex or whirling blast in the space 32 which passes downwardly through flue 33 and into the combustion 20 chamber through a short flue 34 and a continuation of the same designated 34^a. Acting against the flame from the burner it carries the products of combustion over the bridge wall 14 through a continuation 34^a 25 of flue 34 and thence forwardly through the working chamber in spirals. The continuation 34^a of flue 34 is small in cross-sectional area relative to the working chamber. It 30 is located preferably close up to the arch 35 35 of the working chamber and is flared in width toward said working chamber as shown in Fig. 2. It will be observed from Fig. 7 that the movement of the products of combustion is from the roof downwardly 35 and outwardly toward the wall in which the working openings 15 are located, and upwardly along the opposite wall. The tendency, therefore, of the flames to issue from the working openings is minimized. The 40 working openings might be arranged on the other side of the furnace by reversing the inclination of ducts 29, 30. This movement of the gases of combustion through the working chamber results in a substantially 45 uniform temperature throughout the chamber. The loss of heat by radiation and the diminution of the velocity of the blast lengthwise of the chamber are preferably compensated by giving the roof or arch 50 35 a slant in the direction away from the bridge wall so as to diminish the cross sectional area of the chamber in this direction. The flames traveling along under the gradually sloping and rounded arch of the working 55 chamber are reflected downwardly upon the articles to be heated which, it will be understood are forced through the working openings 15.

I have shown the invention as embodied 60 in an oil burning forge furnace. Obviously the principles of the invention might be applied to furnaces quite different in their design, construction and purpose. Therefore I do not wish to be understood as limiting 65 the invention to the precise constructions,

arrangements and devices shown and described except so far as certain of the claims are specifically so limited. I have found that a furnace constructed as above described is very economical of fuel. This is 70 due in part to the fact that there are no waste stack gases. The furnace preferably has no stack. The burned gases may escape through the ordinary slag opening at the end of the working chamber remote from 75 the bridge wall, or the wall or roof of the furnace may be formed with an opening for that purpose. The compressed air supplied by the burners serves to completely break up and atomize the oil. The fan blast 80 surrounding the atomizing nozzle supplies the oxygen needful for combustion. Steam might be used in place of the compressed air. In most furnaces of this general type in which the products of combustion are 85 carried into the flames chamber by an air blast, it is necessary to use a high power blast. I have found it possible to use a blast of comparatively low pressure, obtaining just as high a temperature in the working 90 chamber which, moreover, is uniform from end to end.

I claim:

1. A stackless furnace comprising a horizontally disposed working chamber having 95 an opening at one end smaller in height and width than said chamber, a burner located outside said chamber below the opening, and means whereby a vertical draft may be applied to the gases of combustion from 100 said burner to carry same through said opening and lengthwise of said working chamber by a spiral movement.

2. A stackless furnace comprising a horizontally disposed working chamber of diminishing cross-sectional area from end to end, and provided with working openings, and means for introducing gases of combustion into the chamber at the large end and imparting a whirling movement to the same which carries said gases horizontally through 110 the chamber by a spiral movement, the axis of which is transverse of the said working openings.

3. A stackless furnace comprising a horizontally disposed working chamber having a working opening in one side thereof, and means for introducing gases of combustion into said chamber at one end and imparting a whirling movement to the same, which carries said gases horizontally through said chamber in a spiral movement, the axis of which is longitudinal of the chamber; the working opening being arranged with respect to the direction of the spiral movement 115 so that the gases in that side of the chamber first impinge upon the wall and then move over and away from the opening toward the adjacent wall.

4. The combination with a furnace pro- 120

- vided with a working chamber, a combustion chamber and a bridge wall between the same, of means for supplying fuel and air to the combustion chamber, and means for subjecting the products of combustion to an air blast which carries them over the bridge wall and forward spirally through said working chamber, said furnace being constructed so that the cross sectional area of the working chamber is diminished in the direction away from the bridge wall. 5
5. The combination with a furnace provided with a working chamber, a combustion chamber and a bridge wall between the same, of means for supplying fuel and air to the combustion chamber in the form of a vertical flame, and means for subjecting said flame to a vortical air blast which carries the flame over the bridge wall and forward spirally through said working chamber. 10
6. The combination with a furnace provided with a working chamber, a combustion chamber and a bridge wall between the same, of means for supplying fuel and air to the combustion chamber, the furnace being formed with a pair of air blast ducts directed one toward the other but slightly out of alinement so as to produce a vortical air blast back of said flame. 15
7. The combination with a furnace provided with a working chamber, a combustion chamber and a bridge wall between the same, of means for supplying fuel and air to the combustion chamber, the furnace being formed with a pair of air blast ducts directed one toward the other, one having a slight inclination upward and the other a slight inclination downward from the horizontal, and with a flue leading from the meeting place of the aforementioned ducts into the combustion chamber on the opposite side from the bridge wall. 20
8. The combination with a furnace comprising a working chamber, a combustion chamber and a bridge wall between the same, of a vertical burner extending into the bottom of said combustion chamber, said furnace being provided with a pair of air blast ducts back of said combustion chamber and directed one toward the other but out of alinement so as to produce a vortical blast, and with a flue leading from the meeting place of the aforementioned ducts into the upper part of the combustion chamber on the side opposite the bridge wall. 25
9. The combination with a furnace comprising a working chamber which has an intake in one end and is substantially closed at the other end, of means for introducing gases of combustion into said working chamber and imparting a vortical movement thereto which carries the same forward spirally through said chamber toward the closed end, the side wall of the working chamber against which the products of combustion impinge in their downward movement being provided near the bottom with a working opening. 30
10. The combination with a furnace comprising a working chamber having a working opening in one side, of means for introducing gases of combustion into said working chamber at one end thereof and imparting a vortical movement thereto which carries said gases forward through said chamber with a spiral movement, the axis of which is substantially parallel to the side having the working opening therein, and the direction of which causes the gases to move inwardly away from said working opening. 35
11. In a furnace, the combination of a combustion chamber having an opening, a working chamber communicating with the combustion chamber through said opening, means for producing a vortical air blast back of the opening between said chambers, and means for atomizing and burning a liquid fuel and for carrying the flame into contact with said vortical air blast. 40
12. In a furnace, the combination of a combustion chamber having an opening, a working chamber communicating with the combustion chamber through said opening, means for producing a vortical air blast back of the opening between said chambers, an atomizing liquid fuel burner in said combustion chamber, and means for directing a draft of air against the flame from said burner carrying the same into contact with the vortical air blast. 45
13. A furnace comprising a working chamber, a combustion chamber, a connecting flue between the same of smaller cross-sectional area than the working chamber, a vertically arranged burner in said combustion chamber, an air duct which leads to the combustion chamber back of and in line with said connecting flue, and means for admitting an air blast into said air duct so as to impart a vortical movement to the products of combustion and to carry said products of combustion through said flue and into the working chamber. 50
14. A furnace comprising a horizontally disposed working chamber having an arched roof, a combustion chamber, a flue smaller in length and width than the working chamber which connects said chambers and opens into the working chamber above the floor and close to the arch thereof, an air flue which leads to the combustion chamber back of and in line with said connecting flue, and means comprising intersecting air ducts arranged eccentrically and communicating with said air flue so as to provide for the introduction of a blast of air into said air flue to carry the products of combustion with a vortical movement through said connecting flue and working chamber. 55

15. A furnace comprising a horizontally disposed working chamber having an arched roof, a combustion chamber, a flue smaller in length and width than the working chamber which connects said chambers and opens into the working chamber above the floor and close under the arch thereof, the arch of said working chamber sloping downwardly away from the flue, an air flue which leads to the combustion chamber back of and in line with said connecting flue, and means comprising intersecting air ducts arranged eccentrically and communicating with said air flue so as to provide for the introduction of a blast of air into said air flue to carry the products of combustion with a vertical movement through said connecting flue and working chamber. 70
16. A furnace comprising a working chamber, a combustion chamber, a flue of smaller cross-sectional area than said working chamber which connects said chambers, a burner in said combustion chamber, an air duct which leads to the combustion chamber back of and in line with said connecting flue, and two branch flues which intersect at an angle to each other at the inlet end of said air duct. 75
17. A furnace comprising a working chamber, a combustion chamber, a flue of smaller cross-sectional area than said working chamber, which connects said chambers, a burner in said combustion chamber, an air duct which leads into the chamber back of and in line with the connecting flue, and two branch air ducts which are eccentrically arranged and which open into the air duct on opposite sides thereof. 80
18. A furnace comprising a working chamber, a combustion chamber, a flue of smaller cross-sectional area than the combustion chamber which connects said chambers, a burner in said combustion chamber, an angular air duct which leads to the combustion chamber with its discharge end back of and in line with said connecting flue, and branch flues which intersect at an angle to each other at the end of said air duct. 85
19. A furnace comprising a working chamber, a combustion chamber, a flue smaller in height and width than the working chamber which connects said chambers and is flared in width in the direction toward the working chamber, an air duct which leads to the combustion chamber back of and in line with said connecting flue and intersecting air ducts communicating with said first-named air duct. 90
20. A furnace comprising a horizontally disposed working chamber formed with an arched roof, a combustion chamber, a flue smaller in height and width than the working chamber which connects said chambers opening close under the arch of the working 95
- chamber and is flared in width in the direction of said working chamber, a burner in said combustion chamber, an air duct which leads to the combustion chamber back of and in line with said connecting flue, and a pair of intersecting air ducts communicating with the first-mentioned air duct. 100
21. A furnace comprising a horizontally disposed working chamber having a bridge wall at one end formed with a flue up under the arch of said working chamber, a combustion chamber back of said wall and a burner arranged in said combustion chamber, said furnace being provided with an air duct arranged to deliver blasts of air against the products of combustion as they are delivered from said combustion chamber, and eccentrically arranged intersecting air ducts communicating at their intersection with said first-mentioned air duct. 105
22. A furnace comprising a horizontally disposed working chamber having a bridge wall at one end formed with a flue close up under the arch of said working chamber, a combustion chamber back of said bridge wall, and a burner arranged in said combustion chamber, said furnace being provided with an air duct arranged to deliver blasts of air against the products of combustion as they are delivered from said combustion chamber, and with eccentrically arranged air ducts which intersect at an angle to each other and communicate at their point of intersection with said first-mentioned air duct. 110
23. A furnace comprising a horizontally disposed working chamber having a bridge wall at one end formed with an opening near the top, a combustion chamber back of said bridge wall, a vertically arranged burner in said combustion chamber, a flue connecting said combustion chamber with said working chamber, said furnace being provided with an air duct arranged back of said combustion chamber and in line with said flue, and with a pair of eccentrically arranged intersecting air ducts communicating at their intersection with said first-mentioned air duct. 115
24. A furnace comprising a horizontally disposed working chamber, a combustion chamber, a flue smaller in length and width than the working chamber which connects said chambers and opens into the working chamber above the floor and close to the roof thereof, an air flue which leads to the combustion chamber back of and in line with said connecting flue, oppositely disposed air ducts communicating with said air flue and arranged to direct impinging blasts of air into said air flue so as to carry the products of combustion from said combustion chamber through said connecting flue and working chamber. 120
25. A furnace comprising a horizontally 125

disposed working chamber, a combustion chamber, a flue smaller in length and width than the working chamber which connects said chambers and opens into the working 5 chamber above the floor and close to the roof thereof, an air flue which leads to the combustion chamber back of and in line with said connecting flue, oppositely dis-

posed air ducts communicating with said air flue and arranged to cause blasts of air 10 therefrom to mutually impinge, thereby breaking up the currents of air.
